UNITED STATES PATENT OFFICE.

GEORGE F. ROYER, OF WILKES-BARRE, PENNSYLVANIA.

DESIGN FOR AN AIR-HOSE STAND.

57,271.

Specification for Design.

Patented Mar. 8, 1921.

Application filed June 14, 1920. Serial No. 389,030. Term of patent 14 years.

To all whom it may concern:

Be it known that I, GEORGE F. ROYER, a citizen of the United States, residing at Wilkes-Barre, in the county of Luzerne, State of Pennsylvania, have invented a new, original, and ornamental Design for Air-Hose Stands, of which the following is a specification, reference being had to the accompanying drawings, forming part thereof, in which:—

Figure 1 is a side elevation of an air hose stand showing the new design; and

Fig. 2 is a front elevation of the stand shown in Fig. 1.

The stand is adapted to contain a reel upon which an air hose for supplying compressed air is wound when not in use and unwound when used.

I claim as my invention:

The ornamental design for an air hose stand, as shown.

In testimony whereof I affix my signature.

GEORGE F. ROYER.
